UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

ROOFING ELEMENT

Original application filed September 17, 1921, Serial No. 501,443. Divided and this application filed August 26, 1929. Serial No. 388,457.

The present invention relates to roofing elements which are adapted to be applied to a building structure for the purpose of providing an improved weatherproofing covering, and particularly pertains to roofing strips having oblique off-set sides and surface lines co-operating to divide the surface into separate areas, whereby the strips may be applied on a roof structure in overlapping diagonal courses, simulating individual shingles. Means are provided on one end of the strip or slab for separating each stepped portion on the strip from the divided areas of the adjacent underlying strip.

This case is a division of application Serial No. 501,443 filed September 17, 1921 and issued September 24, 1929 as Patent No. 1,729,912.

Heretofore roofing strips or slabs have been serrated at intervals on one edge to provide a series of exposed tabs for simulating individual shingles when the strips or slabs are laid horizontally in overlapping courses. The tab ends are free and have a tendency to curl the same as individual shingles inasmuch as there are no means for fastening them.

In the present invention, the strip or slab is cut obliquely from a prepared roofing sheet, or made up of overlapping individual elements, with the edges stepped to form tab designs in conjunction with dividing lines or marks formed on the surface to complete the outline of the designs. With this construction, only a portion of each tab is free and hence they are prevented from curling.

For a better understanding of the invention, reference will be made to the accompanying drawings, in which,

Fig. 1 is a plan view of a roofing strip embodying the present invention;

Fig. 2 is a section of a roofing covering composed of roofing strips shown in Fig. 1; and

Fig. 3 is a plan view of a modified roofing strip comprising overlapped stepped shingles.

Referring now to these drawings (Figs. 1 and 2) the novel and improved roofing prod-

uct is typified by an oblique roofing strip or slab 2 cut from a sheet of prepared roofing with the two opposite sides stepped at 3. Dividing lines 4 co-operate with the stepped portions for delineating the surface to simulate rectangular individual shingles such as wood shingles or the like. One end of the strip is recessed at 5 to provide a spacing means 6, this single spacing means functioning to space each simulated individual shingle from the simulated individual shingles of the underlying strip. In horizontally laid strips of this design, it would be necessary to provide spaced recesses which would leave all of the tab ends free and subject to curling.

The same novel and improved strip or slab structure may be obtained (Fig. 3) by overlapping a series of individual shingles 7 in stepped relation, any one or all of which may be spaced at 5¹ to provide spacing means 6¹.

In the present invention, the tabs are adapted to be formed without making any cuts in the body of the strip that would result in leaving the tab ends free. Only the recess in the end of the strip is necessary for providing a spacing means which spaces all the tabs to simulate spaced individual shingles.

While I have shown certain specific embodiments for carrying my invention into effect, it is apparent that various other designs may be produced without departing from the spirit of the invention.

I claim:

1. A roofing strip comprising an elongated body having the surface delineated to simulate a series of individual shingles arranged diagonally in offset relation with tabs on the weather exposed edge, and a spacing means on one end of the strip for spacing the stepped tabs from the tabs of an adjacently laid strip.

2. A roofing strip comprising an elongated body having the surface delineated to simulate a series of uniformly designed individual shingles arranged diagonally in offset relation with tabs on the weather exposed edge, and a spacing means on one end of the strip.

for spacing all the tabs of the strip from the tabs of an adjacently laid strip.

3. A roofing covering composed of overlapping courses including strips, each of which comprise an elongated body having the surface delineated to simulate a series of individual shingles arranged diagonally in offset relation with tabs on the weather exposed edge, and a spacing means on one end of the strip for spacing the stepped tabs from the tabs of an adjacently laid strip.

4. A roofing covering composed of overlapping courses including strips, each of which comprise an elongated body having the surface delineated to simulate a series of uniformly designed individual shingles arranged diagonally in offset relation with tabs on the weather exposed edge, and a spacing means on one end of the strip for spacing all the tabs of the strip from the tabs of an adjacently laid strip.

Signed at Chicago, in the county of Cook and State of Illinois, this 24th day of August, 1929.

25

ALBERT C. FISCHER.
